Inventor

George W. Wrocklage

Patented Nov. 15, 1927.

UNITED STATES PATENT OFFICE.

GEORGE W. WROCKLAGE, OF HACKENSACK, NEW JERSEY.

CONCRETE FORM.

Application filed February 21, 1927. Serial No. 169,816.

This invention relates to improvements in concrete forms and has for an object to provide a metal form for concrete, which may be readily removed.

5 Another object is to provide a metal form for concrete, which may be set up in any size desired.

Still another object is to provide a form for concrete, which may be left in the concrete for reenforcement.

With these and other objects in view, I have invented an improved form for concrete, illustrated in the accompanying drawings, in which:

15 Figure 1 is an elevational view of my invention including upright reenforcing members.

Figure 2 is a bottom plan view thereof;

Figure 3 is a detail view of the attaching handle; and

Figure 4 is a sectional view, taken on line 4 4 of Figure 3.

Figure 5 is an enlarged perspective view of a portion of one of the handles.

25 Figures 6 and 7 are details of one of the latch devices and the locking wedge.

Figure 8 are enlarged perspective views of one pair of the pivot lugs of the handle members.

30 Figure 9 are enlarged perspective views of one pair of the latch devices.

Figure 10 is a view of one of the reenforcing members illustrating a modification in the construction.

35 Like reference characters indicate like parts throughout the following specification and in the several views in the drawings, in which 1 represents the steel reenforcing members, which have a pair of prongs 2, formed

40 at an angle adjacent each end of said reenforcing members. The frame is formed of flat metal pieces 3 which overlap each other as shown at 4, and against each of which one of the reenforcing members 1 rests endwise. A bifurcated lug 5 is formed on each of the metal pieces 3 and between said bifurcations, an elongated slot 6 is provided in said metal pieces. A handle 7 is pivoted to each of said bifurcated lugs, and an en-

45 gaging member 8 is formed on said handle. Said engaging member 8 is a segment of a circle, the center of said circle being at the pivot point 9. Said engaging member is inserted through the slot 6, and a finger 10 which is formed thereon is placed in engagement with one of the prongs 2 on one of the

reenforcing members 1. The handle 7 extends along the metal pieces 3 and is secured thereto by means of a latch 11, formed on each of the metal pieces 3, said latches being formed of a pair of angle irons spaced apart with their ends facing each other. Two of the handles 7 are secured in each of the latches 11, being inserted one at a time and forced apart by a wedge 12 to hold them 60 rigid. When the handle 7 is swung outwardly from the metal pieces 3, the engaging member 8 rotates on its axis 9, and is thus extracted from the concrete. Said engaging member 8 is relatively wedge shaped, 65 its sides diverging from the finger 10, that it may be easily removed from the concrete. After the handles 7 have been moved and engaging members 8 have been removed from the concrete, the metal pieces 3 may be re- 70 moved if desired.

The handles 7 are not removed from the flat metal pieces 3, but are simply turned away from the metal pieces on the pivot or pin 9 and thus 8 is withdrawn from the concrete. The metal form is then removable 80 from the concrete wall.

The members 1 may be of any length desired to correspond to walls or floor beams of different sizes, and differently spaced. If 85 preferred members 1 may be formed of a plurality of sections united by rivets or other means as shown in Figure 10.

With this device a form of any desired dimension may be provided through easy adjustment of the members certain of which may remain in the structure, if desired, for 90 reenforcing purposes.

Having described my invention, that which I claim to be new, and desire to secure by Letters Patent, is:

1. A concrete form, including a plurality of metal pieces, a plurality of reenforcing members, and means for securing said metal pieces to said reenforcing members, said 100 means including a handle pivoted to each of said metal pieces.

2. A concrete form, including a plurality of metal pieces, a plurality of reenforcing members, and means for securing said metal pieces to said reenforcing members, said means including a handle pivoted to each of said metal pieces, and an engaging member formed on each of said handles.

3. A concrete form, including a plurality of metal pieces, a plurality of reenforcing members, and means for securing said metal 110

pieces to said reenforcing members, said means including a handle pivoted to each of said metal pieces, an engaging member formed on each of said handles, a plurality of prongs formed on said reenforcing members, and a finger on each of said engaging members to engage one of said prongs.

4. A concrete form, including a plurality of metal pieces, a plurality of reenforcing members, and means for securing said metal pieces to said reenforcing members, said means including a handle pivoted to one of said metal pieces, and being attachable to two of said metal pieces.

5. A concrete form, including a plurality of metal pieces, a plurality of reenforcing members, and means for securing said metal pieces to said reenforcing members, said means including a handle pivoted to one of said metal pieces, a segment of a circle formed on said handle, and a finger formed on said segment.

6. A concrete form, including a plurality of metal pieces, a plurality of reenforcing members, and means for securing said metal pieces to said reenforcing members, said means including a segment of a circle pivoted to one of said metal pieces, and a finger formed on said segment, the sides of said segment diverging from said finger. 30

7. A concrete form, including a plurality of reenforcing members, a pair of prongs adjacent each end of said members, a flat metal piece resting against each of said members, a handle secured to two and pivoted to one of said metal pieces, a segment of a circle formed on each of said handles extending through a slot in one of said metal pieces and engaging one of said prongs, said pivot being the axis for said 40 segment.

In testimony whereof I affix my signature.

GEORGE W. WROCKLAGE.
